JOHN HENRY BARKER, OF BIRMINGHAM, ENGLAND, ASSIGNOR TO BIRMINGHAM METAL & MUNITIONS COMPANY LIMITED, OF BIRMINGHAM, ENGLAND.

HEAT TREATMENT OF METAL BODIES.

1,085,523.

Specification of Letters Patent.

Patented Jan. 27, 1914.

Application filed June 4, 1913. Serial No. 771,624.

To all whom it may concern:

Be it known that I, JOHN HENRY BARKER, subject of the King of Great Britain, residing at Birmingham, England, have invented 5 certain new and useful Improvements Relating to the Heat Treatment of Metal Bodies, of which the following is a specification.

This invention relates to the local annealing or like heat treatment of tubular metal bodies, and, more especially, the annealing of metal cartridge cases at the ends in which the bullets are secured.

In the manufacture of metallic cartridges 10 for small arms the outer end or short portion of the case embracing the bullet must be necked or reduced in diameter. Such necking involves the performance of work on the metal setting up internal stresses. Where 15 the cases are to be loaded with an explosive in the form of grains or flakes the stresses are removed by an annealing process prior to loading. With cordite or other explosive in the form of tubes, strands or strips it is 20 necessary to insert the charge prior to necking. Hitherto it has not been found practicable to anneal the necks of the cases after loading. The presence of these stresses in 25 the metal is liable when the cases are fired to develop splits or cracks, and if the cartridges are stored for several years, more especially in tropical climes, similar cracks 30 develop spontaneously causing the bullets to become loose or to fall out.

35 With this invention the annealing is effected by heating electrically only the necked or unloaded portions of the cases, and at such a rate that the operation occupies insufficient time for the other portions of the 40 cases to attain a temperature liable to ignite the charge, or at such a rate that such portions can readily be maintained at a safe temperature by an air current or other equivalent means.

45 The invention comprises means as herein-after described for automatically passing an electric current through the cartridge necks.

Referring to the accompanying sheet of 50 explanatory drawings, the diagram illustrates by vertical section one convenient form of apparatus for carrying the invention into effect for the annealing of cartridge cases.

A vertical reciprocating head or plunger 55 *a* has attached to it a pair of electrodes *b*

and *c*, one of which (*b*) comprises an annular element which is insulated from the other (*c*) and is adapted to bear on the cartridge case *d* below the neck. The electrode *c* is a plain or plug like element mounted 60 coaxially with the annular electrode *b* and adapted to bear on the outer end of the neck of the case as shown in the diagram. The annular electrode is carried by spring controlled rods *e* from a plate *f* which is attached to the lower end of a plunger *g* arranged to slide within the plunger *a* and maintained in its lowermost position by a spring *h*. Suitable electrical insulation *i* is provided between the parts *a* and *g*, and 65 also between the parts *f* and *g*. The annular electrode *b* is connected to the source of electricity through the flexible conductor *j*, the supporting flange or plate *f* and a conductor *k*, while the plug or plain electrode *c* 70 is connected to the source of electricity by flexible conductors *l* attached to a collar *q* on the part *a* from which it is separated by insulation *i*.

At a convenient position in the circuit is 75 arranged a switch which is preferably operated with the reciprocation of the plunger *a* or other part of the machine in such a manner that the electrical energy is not supplied until both electrodes are in their position on the cartridge and is interrupted before the electrodes are removed from the cartridge.

The switch is illustrated diagrammatically in the drawings by an arm *r* secured to *a* and 80 fitted with a brush or other contact *s* which is adapted to join the fixed contacts *t*. The movement of *a* against the spring *h* after the electrodes have been brought into contact with the case *d* is utilized to close the 85 switch. The corresponding reverse movement opens the switch before the electrodes are separated from the case *d*.

Completion and interruption of the supply of energy may be performed at any suitable position in the circuit. In the case of an alternating current, the switch is preferably placed in the primary coil of a transformer, and in the case of direct current the switch may be placed in circuit with the 105 magnet coils of a dynamo by which the required current is generated. In both arrangements the object is to place the switch in the part of the system where the current is least.

The cartridges are preferably moved into and out of the operative position by any ordinary intermittently revolving horizontal table indicated diagrammatically by *m* and 5 formed with suitable apertures or pockets *n*. Operation of the table is effected by any ordinary means.

When a case *d* is brought by the table *m* into position beneath the reciprocating head 10 *a* the latter descends until the annular and plug electrodes *b* and *c* make contact with the case at the parts above mentioned. The manner of supporting the electrode *b* through rods *e* from the flange *f* insures 15 proper contact of both electrodes with the cartridge case notwithstanding any slight variations in the length of the case. Further movement of the reciprocating head *a* completes the electric circuit through the 20 switch aforesaid, and in consequence current flows to the portion of the case between the electrodes. During such extra movement of the head or plunger *a* the plunger *g* remains stationary. By employing a large current 25 the neck of the case can be raised practically instantly to the required temperature. The magnitude of the current varies for different classes of work, but the necessary amount for any particular kind of work can readily 30 be determined.

It is advantageous not to effect a perfect electrical contact at the outer end of the case, as an imperfect contact tends to produce greater heating at that part than when 35 the contact is complete, and in consequence the greatest heat is produced at the part of the case remotest from the explosive. Ordinarily the ends of the cases are slightly rough and such roughness is sufficient to produce a slightly imperfect contact with the plunger which results in the aforesaid greater heating at the extremity of the case. After heating the current is interrupted, 40 the electrodes are withdrawn and the cartridge is removed. The operation is then 45 repeated on the next case.

By proceeding as above described the necks of the cartridges can so rapidly be heated and the amount of heat produced is 50 so quickly dissipated by the surrounding air after the circuit has been broken that no time is allowed for undue heating of the body of the cartridge and its contained charge. In consequence the annealing operation is quite safely as well as effectively performed.

If desired an air blast from a jet *o* may be directed on to the body of the case during heating and to expedite subsequent cooling, but this is not essential. Also, if desired, a cover plate may be placed over the neck prior to heating to protect the body part from heat, or the electrode *b* may be water cooled for preventing excessive heating 55 of the main portion of the case. A per-

forated guard *p* may be arranged around the electrode *e* if desired.

The invention while especially suitable for annealing cartridge cases when loaded as above described is not limited to such use, 70 as it may be employed for annealing before loading. Also it may be utilized for such purposes as the local annealing or heating of other like tubular articles. Further, the invention is not limited to the mechanical details herein described as these may be varied 75 to meet different services and requirements.

Having thus described my invention what I claim as new and desire to secure by Letters Patent is:—

1. In means for the electrical annealing or like heat treatment of metal cartridge cases and like tubular articles, the combination comprising an annular and a plain electrode adapted to make contact with the article at the ends of the part to be treated, and means producing conjoint and relative movements of the electrodes, substantially as described.

2. In means for the electrical annealing or like heat treatment of metal cartridge cases and like tubular articles, the combination comprising an annular and a plain electrode adapted to make contact with the article to be treated, a plunger carrying both electrodes and means permitting relative axial movements of the electrodes, substantially as described.

3. In means for the electrical annealing or like heat treatment of metal cartridge cases and like tubular articles, the combination comprising a plunger, an electrode rigidly secured to said plunger, a second electrode carried by but insulated from said plunger and movable in an axial direction relatively thereto, substantially as described.

4. In means for the electrical annealing or like heat treatment of metal cartridge cases and like tubular articles, the combination comprising a plunger, a plain electrode rigidly secured to said plunger, a flange secured to but insulated from said plunger, rods depending from the flange and movable therethrough, an annular electrode carried by said rods, and springs in conjunction with the rods, substantially as described.

5. In means for the electrical annealing or like heat treatment of metal cartridge cases and like tubular articles, the combination comprising a pair of inner and outer telescopic plungers, an annular and a plain electrode relatively movable in an axial direction and carried by the inner plunger, and means actuated with the movements of the outer plunger whereby an electric circuit is closed and opened, substantially as described.

6. In means for the electrical annealing or like heat treatment of metal cartridge cases and like tubular articles, the combination

comprising a pair of inner and outer telescopic and relatively insulated plungers, a spring inserted between the plungers, a plain electrode rigidly secured to the inner plunger, a flange secured to but insulated from the inner plunger, rods depending from and movable through the flange, an annular electrode carried by the said rods, springs inserted between the rods and the flange, substantially as described.

7. In means for the electrical annealing or like heat treatment of metal cartridge cases and like tubular articles, the combination comprising a pair of inner and outer telescopic and relatively insulated plungers, a spring inserted between the plungers, a plain

electrode rigidly secured to the inner plunger, a flange secured to but insulated from the inner plunger, rods depending from and movable through the flange, an annular electrode carried by the said rods, springs inserted between the rods and the flange, and a switch actuated by the outer plunger, substantially as described. 20

In testimony whereof I have signed my name to this specification in the presence of two subscribing witnesses.

JOHN HENRY BARKER.
